SUCTION BLAST GUN

Ralph R. Garver, Hagerstown, Md., assignor to
 Pangborn Corporation, Hagerstown, Md., a corporation of Maryland

Application August 29, 1950, Serial No. 182,023

1 Claim. (Cl. 51—11)

1

This invention relates to particle blasting guns for abrasive-particle-blasting machines and more particularly blasting guns that are operated by a stream of blasting fluid under pressure.

Among the objects of the present invention is the provision of a particle blasting gun of highly efficient, simple and compact construction.

Additional objects of the present invention include particle-blasting guns that can be used to enter small openings and cavities the internal surfaces of which are to be subjected to the blasting treatment, and that can be used with wet or dry abrasive.

The above as well as other objects of the present invention will be more readily understood from the following description of several of its exemplifications, taken in conjunction with the appended drawings wherein:

Fig. 1 shows a vertical cross-section of a particle blasting gun in accordance with one embodiment of this invention;

Fig. 2 is a sectional view along 2—2 of Fig. 1;

Fig. 3 is a plan view of the blasting gun shown in Figs. 1 and 2; and

Fig. 4 is a view similar to Fig. 2 of a modified form of blasting gun exemplifying the present invention.

The gun of Figs. 1, 2 and 3 comprises two substantially parallel lines 1 and 2 for supplying abrasive and air respectively. The lines are shown as of yieldable material such as rubberized fabric and are connected to a nozzle holder or gun body 4.

In this embodiment of the invention, the gun body 4 is an integral iron casting provided as by drilling with separate air and abrasive receiving passages 5 and 6 respectively, that are substantially parallel to each other. The passages 5 and 6 are interconnected by a perpendicular air jet orifice 7. Aligned with the jet orifice is an external opening that extends into the abrasive receiving passageway 6 and receives a nozzle 9. Nozzle 9 extends into the passageway 6 and is retained in place by means of set screw 10 threadedly received in the outer wall of the gun body which is suitably cut away as shown, for convenience. The distance between the innermost end of the nozzle 9 and the outer tip of orifice 7 may vary from about $\frac{1}{4}$ inch to about 1 inch or more as desired.

Abrasive line 1 is received within an enlarged outer portion of passageway 6 and retained in place by means of one or more flat-head wood screws 16 that extend through openings in the surrounding wall portion 15 and engage the wall

2

of line 1. Where more than one screw 16 is used they are staggered vertically along as well as peripherally around the line. The opposite end of passageway 6 is closed as by the threadedly fitted plug 21.

Line 2, a hose similar to line 1, is connected to air receiving passageway 5 by means of nipple 19 which threadedly engages the corresponding end of passageway 5, and around which the line is held 10 as by means of hose clamp 20. A second plug 22 is shown as closing off the opposite end of this passageway. Both plugs may be removed for facilitating the cleaning of the gun body 4.

To simplify the manipulation of the gun, as 15 when it is to be inserted into pipes to blast their internal surfaces, the projecting body portion 15 is shaped to form a reduced skirt over which a rigid tube such as a pipe 3 is received and held as by set screws 11, 12 threadedly engaged in the 20 pipe walls and jammed against the skirt. For improving this anchorage, the pipe is reenforced at the threaded set screw sites by lugs 13, 14 which may be welded in place and are also threadedly engaged by the set screws.

Fig. 4 shows a modified form of construction 25 which differs from that of Figs. 1, 2 and 3 in that the nozzle is completely recessed into the gun body, and the mounting pipe and set screw lugs are dimensioned so as to lie entirely within the 30 outlines of the body periphery.

It has been found that abrasive blasting is a 35 simple and extremely effective treatment by which machined surfaces such as pump cylinders, cylinder bores of piston-type internal combustion engines, or the like can be given a fine finish that is much superior to the conventional honing. Not only does the blasting remove or deemphasize machining or tool marks, but it gives the blasted 40 surface a very fine irregularity or grained appearance that compares favorably with the etched-type surface heretofore used to improve lubrication of the above cylinders. The blasting is easier and less expensive to effect than the etching even without the honing normally used as 45 a preparatory treatment for the etching.

A feature of the present invention is the compactness of the assembly. The nozzle is practically entirely within the gun body, yet is readily replaceable. The air jet passageway is an integral 50 part of the gun body but is not subjected to any serious amounts of erosion and does not have to be replaced. The entire gun can be made in varying sizes, the smallest having an overall diameter of about two inches.

The perpendicularity between the blasting di-

rection and the supply lines is of special significance inasmuch as this is highly advantageous when blasting the inner surfaces of hollow articles. If desired however the nozzle 9 and air jet 1 can be tilted from the perpendicular in a direction toward the plugs, by amounts of up to about 30 degrees. This improves the blasting of surfaces into which the gun cannot be completely inserted. As an alternative construction the plugs 21, 22 may be replaced by imperforate portions of the body so that the passages 5, 6 have blind lower ends.

A highly satisfactory blasting technique employs an abrasive slurry of 80 to 250 mesh sand in water, and an air pressure of 80 pounds per square inch, with the nozzle 9 having a blasting opening $\frac{1}{4}$ inch in diameter. The same sand can also be effectively used in dry condition, although for graining purposes the wet blasting is generally superior. Metal particles can also be used in place of the sand, and the so-called "soft" abrasives such as finely divided corn husks or walnut shells are also suited for use with the gun of the invention.

As many apparently widely different embodiments of this invention may be made without departing from the spirit and scope hereof, it is to be understood that this invention is not limited to the specific embodiments hereof, except as defined in the appended claim.

What is claimed is:

In a compact blasting gun for projecting a

stream of abrasive particles, an elongated integral gun body having two parallel side-by-side passages both extending through its entire length, removable plugs closing off one end of each passage, separate securing elements separately provided at the unplugged ends of the passages to separately receive independent conduits, one for a supply of abrasive particles and the other for a supply of impelling fluid, a discharge nozzle projecting out through a wall of one of the passages for the lateral discharge of the blasting mixture from the gun body, the body wall between the passages including an intercommunication duct aligned with the nozzle for jetting the supplied fluid from the other passage out through the nozzle, said nozzle having its inner end located about $\frac{1}{4}$ " to about 1" from the near end of the duct to cause the jetted fluid to eject a stream of abrasive particles from the other passageway and through the nozzle.
